A. A. SELLE

SHADE AND CURTAIN BRACKET

Filed Feb. 27, 1926

UNITED STATES PATENT OFFICE.

ALBERT A. SELLE, OF JAMAICA, NEW YORK.

SHADE AND CURTAIN BRACKET.

Application filed February 27, 1926. Serial No. 91,182.

This invention relates to curtain brackets and particularly to brackets designed for the support of ordinary roller shades and the support of curtain poles.

One of the objects of the present invention is to provide a curtain pole supporting bracket so constructed that the brackets will allow the curtain or draperies to hang free from end to end on the curtain pole without any interference from the curtain brackets.

A further object is to provide means mounted on the bracket for the support of the trunnions of shade rollers, these supports having screw-threaded engagement with the bracket whereby they may be shifted longitudinally to thereby adjust the device to shorter or longer shade rollers without the necessity of shifting the bracket itself and thus possibly mutilating the window casing.

Other objects will appear in the course of the following description.

My invention is illustrated in the accompanying drawings wherein:—

Figure 1 is a top plan view of a pair of curtain and shade supporting brackets constructed in accordance with my invention.

Fig. 2 is a front elevation of the structure shown in Figure 1;

Fig. 3 is a side elevation of one of the brackets;

Fig. 4 is an inside elevation of the other bracket of the pair; and

Figure 5 is a perspective view of the member 23.

In these figures I have illustrated two brackets A and B, the bracket A being designed for engagement with the flat trunnions used at one end of the shade roller while the bracket B is for engagement with the cylindrical trunnion at the opposite end of the shade roller. Each bracket comprises a base 10, this base being provided with an inwardly extending slot 11 for engagement by a screw or other holding device, and with a small projection 12 designed to act as a small nail or tack.

Extending from the base 10 are the outstanding arms 13 which are integral with the base 10 and with an integral web 14 having an upwardly inclined outer edge. The upper end of the bracket terminates in an upwardly curved curtain pole embracing portion 15 which is approximately semi-

circular in form and opens downwardly. So far I have described features which are common to both brackets; the section A, however, is provided with hub portions 16 having the vertically disposed slots or sockets 17 designed to receive each a flat trunnion such as is found on one end of a vertical shade roller.

The bracket B is formed with the outwardly projecting portions 18 interiorly 65 screw-threaded for the reception of the screws 19 having the heads 20 whereby they may be rotated. There is an upper screw and a lower screw corresponding to the upper and lower sockets on the bracket A. 70 Each of these screws 19 is formed at its extremity with a tubular socket 21 designed to receive the cylindrical trunnion of the vertical curtain pole. Engaging each screw 19 is a wing nut 22 whereby the screw 19 may 75 be locked in its adjusted position.

The purpose of these screws 19 is to provide means for supporting two shade rollers one above the other, and one slightly inward of the other, which means may be adjusted 80 longitudinally with reference to the shade roller to thereby accommodate shade rollers of different lengths without having to shift the brackets toward or from each other. The wing nuts 22, of course, act as jam nuts 85 and lock the adjusting screws in adjusted position.

I have found that in brackets of this type it is not necessary to have openings for two or more screws to hold the bracket 90 to the window casing but that it is amply sufficient if one slot 11 be provided for this purpose and the bracket simply held from any lateral movement by a small projecting prong acting like a brad and forced into 95 the window casing.

For the purpose of supporting the curtain pole C I provide the arcuate member 15 which is approximately semi-circular and which is complementary to the portion 100 16. This arcuate member is preferably formed of a relatively thin and narrow strip of metal bent into an arcuate shape and at one end angularly bent as at 24, and then returned upon itself as at 25, in a 105 slight arc and then angularly bent as at 26. The portion 24 is provided with a slot 27 while the angular end 26 is bifurcated at 28. The inverted hook 15 passes through the slot 27 and the notch or bifurcation 28 110

fits down over the hook. This portion 23 which is complementary to the hook 15, is disposed as illustrated in Figure 3, with the base of the part 23 bearing against the base of the hook 15 and thus the curtain pole is supported as shown in Figure 3, but a gap is left between the extremity of the part 23 and the extremity of the inverted hook 15. Through this gap the curtain hangs and thus while the curtain pole cannot come out from the bracket and is fully supported, yet the draperies will hang perfectly free of the bracket and without any interference with the bracket itself. This allows a free swing of the curtain.

The bracket member 23 is slidable upon the inverted hook 15 in order to permit the insertion of a curtain pole and then permit the bracket member 23 to be shifted to close this gap. It is to be noted that the base 25 of the arcuate member engages against the shoulder formed at the junction of the bracket 13 with the hook 15 and thus this bracket member 23 cannot move beyond a plane connecting the middle of the curtain pole vertically so that under no circumstances can the member 23 interfere with the proper hang of the curtain.

The purpose of this inverted hook 15 and

the arcuate supporting member 23 is to prevent the tearing of curtains by hangers. The adjustable supporting members 19 are adjustable to suit different lengths of shade roller and permit a dark shade and a light shade to be used. Furthermore, these supporting members 19 not only eliminate the necessity of adjusting the brackets toward or from each other as a whole but prevent the shades from jumping out of the brackets.

I claim:

A curtain bracket having an inverted arcuate outwardly projecting curtain pole embracing portion entirely open between its ends and opening downward, and an arcuate member formed of a strip of relatively thin metal curved to conform to the curvature of the inner face of the arcuate portion, said strip at one end being radially extended, then bent rearward in a curve conforming to the body of the strip and then bent inward, the radial portion and the inwardly bent end being slotted to have sliding engagement with said arcuate member.

In testimony whereof I hereunto affix my signature.

ALBERT A. SELLE.
